United States Patent Office.

EDMUND HUDDART, OF PRAIRIE DU SAC, WISCONSIN.

Letters Patent No. 66,591, dated July 9, 1867.

IMPROVED DOOR-HOLDER.

The Schedule referred to in these Letters Patent and making part of the same.

TO ALL WHOM IT MAY CONCERN:

Be it known that I, EDMUND HUDDART, of Prairie du Sac, in the county of Sauk, and State of Wisconsin, have invented a new and useful Improvement in Door-Holder; and I do hereby declare that the following is a full, clear, and exact description thereof, which will enable others skilled in the art to make and use the same, reference being had to the accompanying drawings, forming part of this specification.

This invention consists in the construction and arrangement of parts of a door-holder in such a manner that one portion being attached to a door, and the other part to the wall, the door may be held open and in one position by the friction occasioned by springs, as will be hereinafter described.

Figure 1 represents a side view of the holder, and

Figure 2 an edge view.

Similar letters of reference indicate like parts.

A is a staple attached to a plate which is fastened to the wall by screws or otherwise. B represents the plate to which the staple is attached. C represents the part which is fastened to the door. This is also a plate, to which is attached a stud, D. This stud extends from the plate to the point marked *a*, where it forms a stop against which the staple strikes when the door is swung back. *c c* are two springs attached to opposite sides of the stud D, near the base of the stud at *e*, as seen in fig. 1. The outer ends of these springs are bent inward, forming half circles, or nearly so, the convex sides of which circles are designed to be in contact, or nearly so, with each other, as seen in fig. 2, while the ends turn out in such a manner that when the staple strikes them, the springs open and allow the staple to pass and strike the stud, when the springs immediately close upon it and hold it. A slight pull on the door is sufficient to withdraw the staple when it is desired to close the door. The arrangement of the parts may be reversed, if desired, and the staple placed on the door and the springs on the wall.

What I claim as new, and desire to secure by Letters Patent, is—

The arrangement of staple and plate A B, the stud and plate C D, and the spring *c c*, substantially as shown and described for the purposes herein set forth.

EDMUND HUDDART.
